CLAIM

The ornamental design for a cushion, as shown and described.

DESCRIPTION

In a preferred embodiment, the nature of this product is a cushion, such as a pillow, in flat or rolled configuration, for supporting human body parts.

FIG. 1 is a right, top, front perspective view of a cushion embodying our new design;

FIG. 2 is a top plan view thereof, the bottom plan view thereof being a mirror image of the top shown;

FIG. 3 is a right side elevational view thereof, the left side elevational view thereof being a mirror image of the right side shown;

FIG. 4 is a front elevational view thereof, the rear elevational view thereof being a mirror image of the front shown;

FIG. 5 is a left, top, front perspective view of the cushion of FIG. 1 shown in a rolled configuration; and,

FIG. 6 is a left side elevational view thereof, the right side elevational view thereof being a mirror image of the left side shown; and,

FIG. 7 is a top view thereof.
